MACHINE FOR NAILING SHOE BOTTOMS

Louis P. Tremblay, Lewiston, Maine, assignor to
United Shoe Machinery Corporation, Borough
of Flemington, N. J., a corporation of New
Jersey

Application April 22, 1938, Serial No. 203,629

12 Claims. (Cl. 1—19)

This invention relates to machines for attaching to the bottoms of shoes such elements as the wedges which are included in the heel-portions of some sandals and clogs.

5 In certain types of footwear, there is employed a wedge-shaped piece which may be inserted between the heel-seat of the shoe and a full-length sole or may be attached to the heel-seat and shank at the rear of a short sole. In either 10 case, they commonly taper from their maximum thickness at the back of the shoe to a reduced forward edge in the vicinity of the breast-line, giving a positive support for the entire arch of the wearer's foot. The length of this wedge- 15 portion is such that it cannot be attached properly by a single nailing, so the customary practice is to operate upon it by either two or three heel-attaching machines. For example, the usual five 20 nails may be inserted through the heel-seat of the shoe into the rear of the wedge, then a pair of nails driven at the arch about midway of the wedge, and finally a second pair inserted at the thin edge of the wedge, somewhat to the rear of the breast-line. The driving of the first set 25 presents no special difficulty, but in connection with the other two sets, the counter-portion of the upper is spaced from the rear of the jack, so its locating effect upon the work is lost, and the inclination and curvature of the wedge at its forward 30 extremity requires such an angle between the jack-top upon which the shoe is supported and the hold-down by which the clamping pressure is applied to the bottom, that there is a component of the force tending to displace the work 35 rearwardly. It is an object of the invention to both position the wedge-portion accurately with respect to the jack-top and to retain it against displacement during the operation of the machine.

40 In the attainment of the above object, there is combined with a jack or other shoe-support and a head or member by which pressure is exerted upon the tread-surface, a member mounted upon the pressure member for contact with the 45 rear of the wedge-portion. By thus bringing together the wedge-contacting member and the pressure member, the former may be located most conveniently in the correct wedge-gaging and wedge-retaining relation and there held, regardless of the position of the pressure member. To 50 properly apply the work-clamping force, the pressure member is adjustable, and to arrange for the insertion of the set of nails at the chosen points, the contact member may be retained in 55 different positions upon the pressure member.

In the particular form of the invention disclosed herein, there is a jack of a machine adapted for the inside-nailing of heels and upon which a shoe may be supported for transverse movement, together with a co-operating pressure-head. The 5 pressure-head carries a tread-block upon which is mounted a gage member arranged to position the shoe in its transverse movement. On this block a slide may be movable longitudinally of a jacked shoe, said slide having upon it a fork or abutment situated at the rear of the wedge-portion. The slide may be movable in a recess in a 10 plate secured to the tread-block and may be provided with teeth engaged by a detent movable upon the plate. The arrangement of these teeth is preferably such that the slide is movable freely forward to place the abutment in the desired wedge-engaging position, while rearward movement under the influence of displacing forces exerted upon the wedge is prevented. The detent 15 may, however, be released to permit rearward adjustment of the slide and abutment. If desired, an adjustment of the abutment-fork upon the slide heightwise of the wedge may be provided. In connection with the terms "wedge" or "wedge-portion," it is to be understood that this invention comprehends equally its co-operation with a wedge which is inserted between the heel-seat and sole of a shoe and with one which, at its forward 20 extremity, meets a short sole. The wedge may be considered either as a filler-portion or as a heel.

25 In the accompanying drawing, which illustrates a particular embodiment of the invention, 30 Fig. 1 shows in side elevation portions of a jack and the hold-down of the machine for attaching heels by inside-nailing, and with which is associated my improved positioning and retaining means, and

35 Fig. 2 is a section on the line II—II of Fig. 1. 40 At 10 appears the upper portion of a shoe-supporting jack, in vertical passages in which operate drivers 12 for the insertion in the jacked work of nails N supplied to the passages. A pressure-head, a portion of which is shown at 14, is 45 movable toward and from the jack, serving, in the usual manner, to clamp thereon a shoe and a heel-portion to be attached. Guided in segmental ways 16 in the head is a tread-block 18 adjustable as to angle, fore and aft of the jack, by a 50 worm and worm-segment 20. To provide for adjustment transversely of the jack, the block 18 has a lower section 22 which may be varied in 55 position in ways 24 upon the upper section and fixed in place by a screw 26. Because of the

rather steeply inclined surface which the block 22 is called upon to engage with work of the character to which this invention especially applies, the lower tread-surface 28 is correspondingly inclined. This furnishes a mean relation between the elements of the gearing 20, such that there may be substantial adjustment of the angle of the block in opposite directions, the worm still remaining in full mesh with the segment.

10 The under, tread-contacting surface 28 of the block 22 is herein disclosed as upon a plate 30, secured upon the block by screws 32 and dowel-pins 34. In the upper side of the plate is a slot or recess 36, this slot extending longitudinally of a jacked shoe. In the slot, a slide-bar 38 is movable and has at its forward extremity a depending angular portion 40, upon which is mounted an abutment, shown as in the form of a fork 42, the arms of which may be padded at 44. Accidental withdrawal of the bar is prevented by a pin 45 rising from its inner end. The fork is for engagement by such a work-piece as a wedge-portion W, which preferably has been partially attached to the insole i of a shoe S by 25 nails n. The fork may be secured to the bar-portion 40 at different distances from the bar, and therefore from the tread-surface of the wedge W, by a slot-and-screw connection 46. Formed in one edge of the bar are ratchet-teeth 48 inclined inwardly and rearwardly. In the plate 30 adjacent to the ratchet-teeth is a recess 50, in which a detent 52 is pivoted for engagement with the teeth under the influence of a spring 54. A projecting tail 56 of the detent lies outside the recess, where it may be actuated by the operator to release the bar.

It may be assumed that the shoe S with its partially attached wedge-portion W comes to the nailing machine which is equipped, in accordance 40 with the present invention, for the insertion of the nails N at the forward extremity of the wedge. To prepare for the location of the desired area of the wedge over the drivers 12 which are to be used, the operator may either press the bar 38 from him, the detent 52 yielding, or he may 45 release said detent by pressure upon the tail 56 and then draw the bar to the proper point. The inclination of the tread-contact-surface 28 upon the block 22 will approximate the angle at which lies the outer surface of the wedge or the overlying surface of the outer sole s when the insole i is in most complete engagement with the jack-top, or the angle of the surface 28 may be more 50 exactly adjusted by the gearing 20, this movement being in the plane of angular adjustment 55 of the block. Having jacked the shoe, the operator lowers the pressure-head 14, and before the surface 28 contacts with the work, he slips back the shoe upon the jack-top, until it is correctly located by its engagement with the fork 42.

60 Then, final clamping pressure is applied, and the attaching nails driven. In addition to the effective vertical pressure, the action of the inclined surface 28 upon the inclined work-surface will produce a horizontal component, the effect of which will be to tend to displace the wedge and, with it, the shoe rearwardly, or toward the end of the wedge of greatest height. This force, however, is resisted by the fork, which holds the work securely in place against displacement. It 70 will be seen that since the locating and retaining abutment is mounted directly upon the angularly adjustable tread-block, and since its own adjustment is always parallel to the tread-engaging surface of the block, when the abutment

has been arranged in the chosen relation heightwise of the wedge, it will always so remain, regardless of adjustments.

Having described my invention, what I claim as new and desire to secure by Letters Patent of the United States is:

1. In a machine for nailing wedge-portions to shoes, a shoe-support, a member co-operating with the support and contacting with the bottom of a supported shoe to exert pressure upon the tread-surface of the wedge-portion, means for moving the support and pressure member relatively to clamp together the wedge-portion and shoe, a member mounted upon the pressure member for contact with the rear of the wedge-portion, and means arranged to retain the contact member in different positions upon the pressure member. 10
2. In a machine for nailing wedge-portions to shoes, a shoe-support, a member co-operating with the support and contacting with the bottom of a supported shoe to exert pressure upon the tread-surface of the wedge-portion, means for moving the support and pressure member relatively to clamp together the wedge-portion and shoe, a member mounted upon the pressure member for contact with the rear of the wedge-portion, and means arranged to retain the contact member in different positions upon the pressure member against movement away from the wedge-portion while it is freely movable in the opposite direction. 15
3. In a machine for nailing wedge-portions to shoes, a shoe-support, a member co-operating with the support and contacting with the bottom of a supported shoe to exert pressure upon the tread-surface of the wedge-portion, means arranged to differently position the pressure member with respect to the work, means for moving the support and pressure member relatively to 20 clamp together the wedge-portion and shoe, and a member mounted upon and variable in position with the pressure member for contact with the rear of the wedge-portion. 25
4. In a nailing machine, a jack upon which a shoe may be supported for transverse movement, a pressure-head movable toward and from the jack, a tread-block carried by the pressure-head, and a gage member mounted upon the tread-block and arranged to position the shoe in its 30 transverse movement by engagement with the rear of a heel-portion. 35
5. In a nailing machine, a jack, a pressure-head movable toward and from the jack, a tread-block carried by the pressure-head, and a rear gage member mounted upon the tread-block and by which the position of the work may be determined when applied to the jack, the mounting of the gage member allowing it to be moved longitudinally of a shoe upon the jack. 40
6. In a nailing machine, a jack, a pressure-head movable toward and from the jack, a tread-block carried by the pressure-head, means arranged to vary the angular relation of the tread-block upon the pressure-head, a rear contact member mounted upon the tread-block to be varied in position therewith, and means whereby the operator may secure the contact member in the chosen position. 45
7. In a machine for nailing wedge-portions to 50 shoes, a jack, a pressure-head movable toward and from the jack, a tread-block carried by the pressure-head, a slide movable upon the tread-block longitudinally of a jacked shoe, and an abutment mounted upon the slide at the rear 55

and end of greatest height of the wedge-portion upon the shoe.

8. In a machine for nailing wedge-portions to shoes, a jack, a pressure-head movable toward and from the jack, a tread-block carried by the pressure-head, a plate secured to the tread-block and having a recess, a slide movable in the recess, and an abutment mounted upon the slide at the rear and end of greatest height of the wedge-portion of the shoe.

9. In a machine for nailing wedge-portions to shoes, a jack, a pressure-head movable toward and from the jack, a tread-block carried by the pressure-head, a slide movable upon the tread-

block and being provided with teeth, a detent movable upon the block for engagement with the teeth, and an abutment mounted upon the slide to receive contact of the rear of a wedge-portion upon a jacked shoe.

10. In a machine for nailing wedge-portions to shoes, a jack, a pressure-head movable toward and from the jack, a tread-block carried by the pressure-head, means arranged to vary the angle of the tread-block longitudinally of a jacked shoe, a slide movable upon the tread-block in the plane of angular adjustment there-

of, an abutment mounted upon the slide at the rear of a wedge-portion upon the shoe, and means arranged to vary the position of the abutment upon the slide vertically of the rear of the wedge.

11. In a machine for nailing wedge-portions to shoes, a jack, a pressure-head movable toward and from the jack, a tread-block carried by the pressure-head, a plate secured to the tread-block and having a recess, a bar movable in the recess and provided with a series of teeth, and a detent movable upon the plate and co-operating with the teeth to retain the bar and fork against rearward movement while permitting free forward movement.

12. In a machine for nailing wedge-portions to shoes, a jack, a pressure-head movable toward and from the jack, a tread-block carried by the pressure-head, a plate secured to the tread-block and having a recess, a bar movable in the recess and provided with a downwardly extending angular end, a fork mounted upon the angular end of the bar for engagement with the rear of a wedge-portion upon a jacked shoe, and means arranged to secure the fork in different positions upon the angular end of the bar.
